(57) **CLAIM**

The ornamental design for a display stand, as shown and described.

DESCRIPTION

FIG. 1 is an isometric view of a display stand in accordance with a first embodiment of the invention.

FIG. 2 is a front elevational view of the display stand in accordance with the first embodiment of the invention.

FIG. 3 is a rear elevational view of the display stand in accordance with the first embodiment of the invention.

FIG. 4 is a first side elevational view of the display stand in accordance with the first embodiment of the invention.

FIG. 5 is a second side elevational view of the display stand in accordance with the first embodiment of the invention.

FIG. 6 is an isometric view of a display stand in accordance with a second embodiment of the invention.

FIG. 7 is a front elevational view of the display stand in accordance with the second embodiment of the invention.

FIG. 8 is a rear elevational view of the display stand in accordance with the second embodiment of the invention.

FIG. 9 is a first side elevational view of the display stand in accordance with the second embodiment of the invention; and,

FIG. 10 is a second side elevational view of the display stand in accordance with the second embodiment of the invention. Any shading on the figures is provided only to distinguish between the flat and contoured portions of the display stands, such shading patterns are not intended to be viewed as part of the claimed display stands. Features shown in broken lines do not form part of the claimed design.

1 Claim, 6 Drawing Sheets
